(57) **CLAIM**

The ornamental design for a barbecue assembly, as shown and described.

DESCRIPTION

FIG. 1 a front view of a barbecue assembly in an unfolded state;

FIG. 2 is a rear view of the barbecue assembly;
FIG. 3 is a left side view of the barbecue assembly;
FIG. 4 is a right side view of the barbecue assembly;
FIG. 5 is a top view of the barbecue assembly;
FIG. 6 is a bottom view of the barbecue assembly;
FIG. 7 is a first perspective view of the barbecue assembly;
FIG. 8 is a second perspective view of the barbecue assembly;
FIG. 9 is a front view of a barbecue assembly in a collapsed state;
FIG. 10 is a rear view of the barbecue assembly;
FIG. 11 is a left side view of the barbecue assembly;
FIG. 12 is a right side view of the barbecue assembly;
FIG. 13 is a top view of the barbecue assembly;
FIG. 14 is a bottom view of the barbecue assembly;
FIG. 15 is a first perspective view of the barbecue assembly;
FIG. 16 is a second perspective view of the barbecue assembly;
FIG. 17 is a front view of a grill element of the barbecue assembly without supporting portion, shown in isolation;
FIG. 18 is a rear view of the grill element of the barbecue assembly, shown in isolation;
FIG. 19 is a left side view of the grill element of the barbecue assembly, shown in isolation;
FIG. 20 is a right side view of the grill element of the barbecue assembly, shown in isolation;
FIG. 21 is a top view of the grill element of the barbecue assembly, shown in isolation;
FIG. 22 is a bottom view thereof;
FIG. 23 is a first perspective view thereof;
FIG. 24 is a second perspective view thereof;
FIG. 25 is an enlarged view taken along circle 25 of FIG. 1;
FIG. 26 is an enlarged view taken along circle 26 of FIG. 1; and,
FIG. 27 is an enlarged view taken along circle 27 of FIG. 7. The broken lines depict portions of the barbecue that form no part of the claimed design. The broken ones immediately adjacent the shaded areas represent the bounds of the claimed design.
